Walter W. Hoyle, Fayetteville, N.Y., assignor to Carrier Corporation, Syracuse, N.Y., a corporation of Delaware

Filed Dec. 11, 1962, Ser. No. 72,807

Term of patent 3½ years

(Cl. D62—4)

FIG. 2

FIG. 3

FIGURE 1 is a perspective view of an air conditioner cabinet embodying my new design;

FIG. 2 is a fragmentary vertical cross-section taken along line 2—2 of FIGURE 1; and

FIGURE 3 is a fragmentary horizontal cross-section taken along line 3—3 of FIGURE 1.

The top and the rear of the unit are substantially plain and the side not shown is substantially like the side shown.

I claim:

The ornamental design for an air conditioner cabinet, substantially as shown and described.
